ATKINS

UNITED STATES PATENT OFFICE.

MAX F. THAU, OF PEORIA, ILLINOIS.

FASTENING DEVICE.

1,262,407.

Specification of Letters Patent.

Patented Apr. 9, 1918.

Application filed May 25, 1917. Serial No. 170,850.

To all whom it may concern:

Be it known that I, MAX F. THAU, a citizen of the United States, a resident of Peoria, in the county of Peoria and State of Illinois, have invented new and useful

5 Improvements in Fastening Devices, of which the following is a specification.

10 My invention relates to improvements in fastening devices, particularly adapted for use in connection with soft collars and the like, though it is capable of various other extended uses.

15 The principal object is the provision of a fastening device which is simple in construction, ornamental in appearance and effective in holding two loose or gaping parts in proper relation to each other.

20 To the accomplishment of the foregoing and such other objects as may hereinafter appear, my invention consists in the combination, construction and arrangement of parts hereinafter described and then sought to be defined in the appended claim, reference being had to the accompanying drawings

25 which shows for the purpose of illustrative disclosure, one embodiment of my invention, it being understood that various changes may be made in practice within the scope of the claim without digressing from

30 my inventive idea.

In the drawings:

Figure 1 represents a perspective view of a collar and neck-tie with a device constructed according to my invention, applied thereto:

35 Fig. 2 is a front view and edge view, respectively, of one form of device constructed according to my invention.

Referring now to the drawings, the number 1 designates a neck-tie, tied four-in-

hand, and the collar 2, having the usual spaced gaping points 3. These pointed portions gape particularly in soft collars, and my invention is designed to hold these parts in their proper position to each other.

45 In Fig. 2 it is seen that it includes the bar 4 having the out-turned ends 5 for the purpose of ornamentation, and having the sharply pointed prongs or securing members 6 mounted on the rear side thereof. These members are arranged so as to point toward each other so that when the device is applied, as in Fig. 1, it will be securely held to the collar and will hold the points of the collar securely in the desired position.

50 It is to be noticed that by making the prongs independent of the bar they may be positioned at any desired point therewith; the device may be readily repaired and the prongs may be formed of a material different from that of the bar, which is especially desirable when the bar is formed of a precious metal. By soldering the prongs, the bar is maintained integral and intact and material is added so as to reinforce the device at the junction of the prongs with the bar. It is therefore seen that I have provided a simple and effective device for the purposes specified.

55 What I claim is:—

A fastening device for soft collars, comprising a bar-like body, and a pair of securing prongs extending inwardly toward each other soldered to the back of the body adjacent each end to reinforce the body at 73 said points of securement, said prongs being formed separate from the body and united thereto by solder so as to leave the body in its original thickness and integrality.

73 MAX F. THAU.
